UNITED STATES PATENT OFFICE

146,231

DESIGN FOR A TIE CLASP OR THE LIKE

Werner F. Oppenheimer, New York, N. Y.

Application August 24, 1946, Serial No. 132,790

Term of patent 14 years

(Cl. D17—10)

To all whom it may concern:

Be it known that I, Werner F. Oppenheimer, a citizen of the United States of America, residing in the Borough of Manhattan, city, county, and State of New York, have invented a new, original, and ornamental Design for Tie Clasp or the like, of which the following is a specification, reference being had to the accompanying drawing, forming part thereof, wherein:

Figure 1 is a front view of a tie clasp or the like embodying my new design, the particular letters of the alphabet shown being merely representative.

Fig. 2 is a side elevation of the tie clasp shown in Fig. 1.

In the drawing the shaded portions represent engraving lines to provide a visual effect of substantial depth to flat lettering on a polished surface.

I claim:

The ornamental design for a tie clasp or the like, as shown and described.

WERNER F. OPPENHEIMER.
